[57] CLAIM

The ornamental design of a combination knob and double pan torchiere lamp, reading lights and table, as shown and described.

DESCRIPTION

FIG. 1 is a perspective view of the combination knob and double pan torchiere lamp, reading lights, and table in accordance with the present invention;

FIG. 2 is a front elevational view thereof;

FIG. 3 is a right side elevational view thereof;

FIG. 4 is a left side elevational view thereof;

FIG. 5 is an enlarged fragmentary right side view of the knob and double pan torchiere head, the lamp being fragmentarily shown for convenience of illustration;

FIG. 6 is a bottom view thereof; and,

FIG. 7 is a partial perspective view illustrating the knob and double pan of the torchiere light in more detail.
